H. A. DAVIS

LAY ASSEMBLY FOR LOOMS

Filed Aug. 17, 1926

UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

LAY ASSEMBLY FOR LOOMS.

Application filed August 17, 1926. Serial No. 129,672.

This invention relates to looms and is more particularly directed to the lay assembly and its combination with the loom frame. It is now the ordinary practice to assemble the weaving instrumentalities directly upon the loom frame and for this purpose the loom parts are brought to the loom frame and assembled individually thereon. This is particularly so with respect to the lay and its attachments. In looms of the downwardly extending lay sword type it is now the usual practice to mount the lower ends of the lay swords upon a rock shaft extending transversely of the loom and held in bearings in the loom frame sides.

Looms are ordinarily grouped in large numbers in the weaving room, and in order to economize space, they are placed as close together as is consistent with the proper operation of the loom parts. It becomes necessary at times to remove the lay rock shaft for various reasons and in order to do this in the weaving room, the entire loom must be swung out of position with its relation to other looms, in order that the long rock shaft may be withdrawn.

One of the objects of the present invention is to provide a lay assembly wherein the lay beam, the lay swords, shuttle boxes and other attachments, such as the reed, for instance, may be assembled as a unit at an assembly station distant from the loom frame, and then as such unit be readily applied to the loom, and incidental to such lay assembly as constitutes the present invention, the construction is so devised that the lay assembly as a unit may be readily removed from the loom while in its weaving position and without disturbing the operation of looms adjacent thereto or removing any of the looms from place.

Other features of the invention and novel combination of parts will best be made clear from the following description and the accompanying drawings of one good form of the invention.

In the drawings, the loom frame and other parts associated therewith are shown in dotted lines, while the features constituting the present invention are indicated in full lines, for the purpose of more clearly elucidating the present invention.

In the drawings, the loom frame 1 may be

of usual construction, which ordinarily 55 comprises a bottom tie bar or member 2 which extends between the loom sides to which it is permanently secured, and similarly, at the rear portion of the loom frame another cross-tie 3 is usually employed and associated with forwardly extending members 4 secured at their ends to the front and rear cross-ties. The loom frame 1, however, may be varied in construction, without departing from the present invention, and usually the cloth take-up roll 6 is mounted in stands 7 secured one at each side of the loom to the cross-tie 2. In looms of the usual type, the lay rock shaft extends between the side frames of the loom and on such rock 70 shaft the lay swords are mounted, in order that the lay may swing to and from the front of the loom during the weaving operation, and when the lay, lay swords and other parts of the loom are assembled at the loom frame, 75 the parts are placed individually in their operative relation directly upon the loom frame.

In accordance with the present invention, the lay, lay swords and other lay attachments are assembled at an assembly station as a unit and thereafter this assembled unit is placed directly in the loom with the parts in their proper relation.

As shown in the drawings, the lay beam 8 may be of usual type provided with the ordinary shuttle race 9, at each end of which the lay beam has mounted thereon the shuttle boxes 10, one at each side of the loom, and extending above the lay race is the reed 90 11 held at its upper end in the rail 12. These parts are usually assembled in operative relation at the loom frame.

In the lay assembly constituting the present invention, the lay beam 8 has secured thereto, as usual, the lay swords 13 and 14, which extend downwardly from the lay beam, and at their lower ends each of the lay swords is provided with a stud shaft bearing 15 which is preferably constituted as a sleeve or 100 collar, as indicated in the drawing.

The loom sides at their lower portions are each provided with a main bearing 16, each of which extends through an opening in the loom sides in which it may be secured by suitable means such as the bolts 17, and mounted in each of the main bearings 16 is a stud shaft 18, one end of which terminates

inside of the loom side frames and the other end of which terminates outside of the side frames, as indicated.

The inner end portion of each stud shaft 5 has secured thereto the stud shaft bearing 15 of the adjacent lay sword, and one good form of securing the stud shaft bearing to its stud shaft may be constituted as bolts 19.

Inasmuch as the lay assembly is to be made 10 at a lay assembly station apart from the loom frame, the present invention contemplates that the lay swords 13 and 14 which are secured at their upper portions to the lay beam, be secured together above the 15 stud shaft bearings by a tie or cross-rod, which, in the present instance of the invention, is shown as the bar or rod 20, the end portions of which are received in sockets 21 projecting from the lay swords and 20 provided with screw bolts 22, whereby the lay swords above the stud shaft bearing 15 are tied together in their proper relation, an operation that may be performed at an assembly station remote from the loom frame, 25 so that the lay, lay swords and attachments may be assembled as a unit and then brought to the loom frame and assembled thereon by the respective stud shafts 18.

Each of the stud shafts 18 extends from 30 the inner side of the loom frame to the outer side thereof, and has mounted on its outer end portion a shoe 23 which may be detachably connected to the stud shaft by a suitable bolt 24. Each of the shoes 23 has 35 its upper surface formed to receive the rocker 25 of the picker sticks 26.

Between the stud shaft bearing 15 at the lower end of each lay sword and the end of the bearing 16, a washer or collar 27 is 40 interposed, and the inner end portion of the rocker sleeve 28 bears upon the outer end of the main bearing 16, with the result that when the stud shafts have secured thereto the stud shaft bearings 15 and the sleeve 28, the stud shafts themselves will be held from 45 endwise movement.

Since the stud shafts 18 do not extend across the loom as is customary with the usual lay rock shaft, the lay assembly unit 50 may be brought to the loom, each of the stud shafts 18 be placed in operative position with the stud shaft bearings 15 secured thereto at the inner end of each stud shaft, and the shoe 23 secured to the outer end 55 portion of the stud shafts. Should it become necessary at any time to remove the lay assembly unit from the loom or to renew the main bearings or other parts, it is only necessary to loosen the bolts 19 and the bolt 24 of the shoe, to enable each stud shaft to 60 be withdrawn, without at the same time disturbing the position of the loom in the weaving room.

By the construction described, which embodies the present invention, the lay and its

attachments may be assembled as a unit at a distant station and then brought to the loom frame as such unit and applied to the loom as hereinbefore described, and similarly, should it be necessary at any time to renew 70 the bearings or other parts or to remove the lay assembly, it is only necessary to withdraw the short stud shafts without disturbing the position of the loom with its relation to other looms in the weaving room. 75

The tie or rod 20 which constitutes part of the lay assembly is preferably secured to the lay swords near the lower end portions thereof above the stud shaft bearings 15, so that the entire lay assembly is rigidly held 80 in proper position for application to or removal from the loom.

What is claimed is:

1. In a loom, the combination of the loom side frames, shaft bearings at the lower portion thereof, a stud shaft mounted in each bearing and terminating on the inside of each side frame, a lay assembly comprising the lay beam and lay swords each having a stud shaft bearing at its lower portion, a 85 tie rod extending between and secured to the lay swords above the stud shaft bearing to prevent relative movement of the lay swords and means for detachably securing the stud shaft bearings to the stud shafts 95 to permit withdrawal of the stud shafts from the stud shaft bearings that the lay assembly may be readily removed from or applied to the loom as a unit while the loom remains in normal weaving position. 100

2. In a loom, the combination of the loom side frames, shaft bearings at the lower portion thereof, a stud shaft mounted in each bearing and terminating at the inside of each side frame, a lay assembly comprising the lay beam and lay swords each having a stud shaft bearing at its lower portion, a tie rod extending between and secured to the lay swords above the stud shaft bearing to prevent relative movement of the lay swords, a picker stick rocker detachably secured to the outer portion of each stud shaft and means for detachably securing the stud shaft bearings to the stud shafts to permit withdrawal of the stud shafts from the stud shaft bearings that the lay assembly may be readily removed from or applied to the loom as a unit while the loom remains in normal weaving position. 110

3. In a loom, the combination of the loom frame having shaft bearings at its lower portion, a separated stud shaft mounted in each bearing, and a lay assembly comprising the lay beam having lay swords secured thereto, a stud shaft bearing at the lower portion of each lay sword, a tie rod extending between and secured to the lay swords above the lay sword bearings, and means for detachably securing each of the lay sword bearings to the adjacent stud 125 130

shaft that the latter may be removed from the bearings to permit the lay assembly to be readily removed from or placed in the loom as a unit.

4. In a loom, the combination of the loom frame having shaft bearings at its lower portion, a separate stud shaft mounted in each shaft bearing for rocking movement therein, a lay assembly comprising the lay beam having lay swords extending downwardly therefrom and provided at their lower ends with a stud shaft bearing, a tie rod extending between and secured to the lay swords above the stud shaft bearings, means for detachably connecting each of the stud shaft bearings to its stud shaft inside the loom frame that the stud shafts may be readily removed from the stud shaft bearings and the lay assembly from the loom as a unit.

5. In a loom, a lay assembly comprising the lay beam having a shuttle race and shuttle boxes, downwardly extending lay swords secured to the lay beam and having bear-

ings at their lower portions, a tie member 25 extending between and secured to the lay swords above the bearings and holding the parts in assembled relation and a separate supporting rocker stud shaft for each of the lay sword bearings that the lay and its attachments may be assembled as a unit and readily applied to or removed from the loom.

6. In a loom, the combination of a lay assembly unit comprising the lay beam and 35 shuttle boxes, lay swords secured at their upper ends to the lay beam and having bearings at their lower ends, a tie rod extending between and secured to the lay swords above the bearings, and a separate 40 stud shaft mounted one at each side of the loom and extending into the adjacent lay sword bearing that the lay and attachments may be assembled as a unit and as such be applied to or removed from the loom. 45

In testimony whereof, I have signed my name to this specification.

HARRY A. DAVIS.
